UNITED STATES PATENT OFFICE.

JONAS J. MOYER, OF OAKLAND, CALIFORNIA.

MOUTH SPECULUM.

1,420,493.

Specification of Letters Patent. Patented June 20, 1922.

Application filed September 20, 1920, Serial No. 411,623. Renewed May 13, 1922. Serial No. 560,818.

To all whom it may concern:

Be it known that I, JONAS J. MOYER, a citizen of the United States, residing at the city of Oakland, in the county of Alameda 5 and State of California, have invented certain new and useful Improvements in Mouth Speculums, of which the following is a specification.

This invention relates to improvements in 10 mouth speculum, particularly to a combined mouth gag and tongue depressor and has for its object the construction of an improved device of this character adapted for use in operations on the throat and adjacent parts.

15 Among the objects of my present invention is to provide a simple and effective means for adjusting and holding apart the teeth engaging clips of the gag. Another object is to provide an improved mounting 20 for the tongue depressor whereby it may be oscillated in a transverse plane and the rear end of the blade depressed against the tongue.

25 A further object of the invention is to arrange the tongue depressor that it may be instantaneously removed from the other part of the instrument and may as readily be placed in position thereon.

With these and other objects in view the 30 invention consists of certain novel features of construction, combinations and arrangements of parts herein illustrated and more specifically pointed out in the appended claims.

35 Reference being had to the drawings forming a part of the specification.

Figure 1 is a view in front elevation of my improved instrument.

40 Figure 2 is a view in side elevation of the same.

Figure 3 is a view in plan of the improved instrument.

Figure 4 is a view in rear elevation of the standard of the instrument.

45 Figure 5 is a view in front elevation of the standard of the instrument with the tongue depressor and its stem removed.

Figure 6 is an enlarged sectional view in the line 6—6 Figure 1.

50 Figure 7 is an enlarged view in perspective of the upper end of the stem to which the tongue depressor is attached.

Referring to corresponding parts in the several views by the same numerals of reference, the instrument comprises a standard comprising a stem 1 having the curved lower

end 2, and having formed on its upper end ears 3. The end of the stem between the ears is curved on a circular arc as shown at 4, for the purpose hereinafter explained. 60

Back of stem 1 is a member 5, on the upper end of which is formed a tooth engaging clip 6. This member extends down, back of the stem 1 and adjacent its upper end is provided with ears 7, which are adapted to be 65 positioned outside of ears 3 and to be pivotally attached thereto by means of screws or rivets 8. The lower portion of member 5 is composed of two parallel bars 9 which are spaced apart from each other so as to form 70 a slot 10.

On the back of the member 5 is disposed a plate 12 having guides 13 formed on its side edges which are adapted to embrace the sides of the bars 9 and slidably mount the 75 plate thereon. From the upper end of this plate extends a ring 14 which has an opposed tooth engaging clip 15 formed, directly opposite the tooth engaging clip 6. The sides of this ring are bent rearwardly as shown at 80 16 in order that when the instrument is positioned in the mouth the ring will fit closely against the outside of the cheeks of the patient.

The tooth engaging clips 6 and 15 are adjustable with respect to each other by the plate 12 being moved longitudinally on member 5. To hold these parts in adjustable position I provide the ratchet mechanism particularly illustrated in Figure 5. 90 In forming this mechanism, plate 12 is provided with a transverse slot 17 in which is slidably mounted a bar 18 which has an end 18' which extends slightly outside of the plate so as to be engaged by the finger to release the ratchet mechanism. This slot 17 extends through the plate and on the inside of the latter has attached a block 19 the ends of which overlap the plate and so hold the bar in the slot. This block is provided with 100 a tooth 20 which engages a ratchet 11 formed on inner edge of one of the bars 9. The side of this block opposite this tooth is recessed and held therein is a flat spring 21 which tends to hold the tooth in engagement with 105 the ratchet.

The tongue depressor consists of a stem 22 having formed on its lower end a loop 23 which serves as a handle. The depressor stem is provided with a shoulder 24 110 which is adapted to engage the lower ends of the spring clips 25 attached to the face.

of the bar 1 and thereby prevent upward movement of the depressor in relation to this bar. The arcuate end 4, closely embraces the depressor stem, thereby acting as a seat for upper end of the latter. To hold the stem in this seat, I provide on the back of stem 22, a hook 26, which extends over the top of arcuate end 4, and engages the rear surface of the latter. The other end of stem 22 is bent at a right angle thereto and extends over the tooth engaging clip 6. This extended end denoted by 27, is provided with the longitudinal slots 28, in which the tongue depressor blade 29 is frictionally held.

Slidably mounted on the bar 1 is a stop block 30 which is adapted to be moved upwardly in the angle between the bar 1 and member 5 and thus to increase and decrease 20 the angle between their members.

In use the clips 6 and 15 are inserted between the teeth of the patient and then moved apart. This causes the member 5 to slide in the plate 12 in the direction of 25 the ratchet 11. The tooth 20 engaging this ratchet prevents movement in the opposite direction and so holds the depressor against the tension produced by the jaws.

The tongue depressor may then be positioned by engaging the hook 26 back of 30 the arcuate end 4 and snapping the lower end between the clips 25. This effectively holds the depressor in position on the member 1 and yet allows a sidewise oscillative 35 movement of the blade 29 with reference to the mouth.

The blade 29 is positioned that is normally depresses the tongue a sufficient amount, and it may be moved longitudinally of the end 27 so as to fit different shaped mouths. In case it is necessary to 40 depress the tongue more than normal and especially the base of the tongue then the lower end of bar 1 is moved away from member 5. Members 1 and 5 being pivotally attached to each other by means of 45 the pins 8, this movement throws the outer end of the tongue depressor blade down and further depresses the back part of the tongue. When these members are thus 50 moved apart, the position may be held by sliding the block 30 up between them.

I claim as new and wish to cover by Letters Patent—

55 1. A speculum comprising a standard, teeth-engaging means to hold the mouth open, a tongue depressor oscillatively mounted on said standard so as to move transversely of the tongue, and an adjustable tongue-engaging blade carried by said tongue depressor.

60 2. A speculum comprising a mouth gag, a standard having an arcuate guide, spring clips carried by said standard, a tongue depressor comprising a stem having its one

end engaged by said spring clips, a pin carried by the other end of said stem adapted to engage said arcuate guide, and a tongue depressing blade extending at substantially right angles to said stem. 70

3. A speculum comprising an adjustable gag for holding the jaws apart, a tongue depressor comprising a tongue-engaging blade and a stem, and means for removably holding said depressor stem on said gag 75 and permitting limited transverse and perpendicular oscillative movement of said blade with respect to the tongue.

4. A speculum, a standard, comprising two members movable in respect to each other, ratchet means for holding said members in adjusted relation, oppositely disposed teeth-engaging clips carried by said members, a tongue depressor oscillatively mounted with respect to said standard comprising a stem, spring means removably holding said stem on said standard, and a tongue depressing blade extending from said stem at substantially right angles thereto. 85

5. A speculum, a standard, comprising two members slidably mounted one on the other, a ring attached to one end of said members, teeth-engaging clips carried by said ring and the other of said members a 95 stem oscillatively mounted on said standard and having a portion extending through said ring and a tongue depressing blade carried by the outer end of said stem which extends through said ring. 90

6. A speculum, a standard comprising a plate, a ring rigidly attached to the upper end of said plate, a member longitudinally movable on said plate, means for adjustably holding said plate relative to said member, 105 teeth-engaging clips on the upper ends of said member and said ring, a rod oscillatively mounted on said standard and forming the handle of a tongue depressing member, an end on said rod bent at right angles 110 to said handle and extending through said ring, and a tongue depressor blade on the outer end of said bent end.

7. A speculum comprising two members relatively movable one on the other, teeth-engaging clips carried by said members means for holding said members in adjusted relation, a rod oscillatively mounted in one of said members and forming a handle, a portion extending from the upper end of 120 said handle and at right angles thereto, and a tongue depressor blade adjustably mounted on the outer end of said bent portion.

8. A speculum comprising a plate and a member relatively movable one on the other, teeth-engaging clips carried by said plate and said members guide on said member, a rod oscillatively mounted on said member, a spring clip removably holding the lower end of said rod, a pin extending from the 125 130

said rod and engaging said guide, and a tongue depressing blade adjustably mounted on the upper end of said rod.

9. A speculum comprising a standard, 5 relatively movable members carried by said standard, teeth-engaging clips carried by said members, a bar oscillatively mounted on one of said movable members in the plane of said clips, and a tongue depressor removably 10 mounted on said bar and oscillatively movable transversely with respect to said clips.

10. A mouth speculum comprising a standard, means carried by said standard for holding the jaws apart, a tongue depressor 15 comprising a stem extending longitudinally of said standard and removably mounted thereon, a blade extending in an angular direction from said standard, and means for permitting a limited oscillative movement 20 of said blade on an axis parallel to said stem.

11. A speculum comprising a standard, means carried by said standard for holding the jaws spread apart, a tongue depressor 25 blade, a stem extending longitudinally of said standard and having its upper end bent at right angles to engage said blade, a pin extending from said bent portion substantially parallel to said stem, an arcuate guide 30 carried by said standard adapted to be engaged by said pin, a spring clip adapted to engage said stem, and a shoulder on said stem adapted to engage the lower edge of said clip to prevent upward movement 35 thereof.

12. A device of the character described a standard comprising two relatively movable members, means for holding said members in adjusted relations to each other, a tooth 40 engaging clip carried by each of said members, a bar pivotally attached to one of said members and adapted to assume an angle with respect to the member, a tongue de- 45 pressor removably mounted on said bar and a block movable between the bar and the

member to which it is attached for varying the angle therebetween.

13. A device of the character described comprising a plate, a tooth engaging clip formed thereon, a member slidably mounted 50 on said plate, a tooth engaging clip formed on said member, ratchet means for holding said member and said plate in adjusted relation, a bar pivotally attached to said member, and a tongue depressor removably held 55 on said bar.

14. A device of the character described, a standard, comprising two relatively movable members, tooth engaging clips carried by 60 said members, a bar pivotally attached to one of said members and a tongue depressor oscillatively mounted on said bar on an axis at right angles to the pivot axis of said bar on said plate.

15. A device of the character described 65 comprising two relatively movable members, teeth engaging clips carried by said members, a bar pivotally attached to one of said members on an axis at right angles to a median line through said clips, an arcuate 70 curved end on said bar forming a recess, a stem seated in said recess, spring holding clips for said stem on the opposite end of said bar, a hook on said stem adapted to engage said arcuate end, an end on said stem 75 formed at right angles thereto and extending between said clips, and an adjustable tongue depressor blade carried by said end.

16. A device of the character described comprising teeth engaging clips, means for 80 holding said clips in adjusted relation, a strip pivotally mounted adjacent one of said clips on an axis at right angles to a median line between the two, a tongue depressor oscillatively mounted on said strip, with its 85 axis parallel to a median line of said clips and a tongue depressor blade extending between said clips.

In testimony whereof I affix my signature.
JONAS J. MOYER.
